UNITED STATES PATENT OFFICE.

HERBERT KIENZLE, OF NEW YORK, N. Y.

SHADE-HOLDER.

1,221,744.

Specification of Letters Patent. Patented Apr. 3, 1917.

Application filed July 15, 1916. Serial No. 109,426.

To all whom it may concern:

Be it known that I, HERBERT KIENZLE, a subject of the Emperor of German, residing in New York, in the county of New York and State of New York, have invented certain new and useful Improvements in Shade-Holders, of which the following is a specification.

This invention relates to and has for the main object to provide an electrical portable or floor lamp with proper light distribution and with certain arrangements to obtain this purpose and specifically to provide a direct arrangement for supporting a certain lamp shade or scarf or reflector in connection therewith. In order to accomplish this object the present invention covers a two part lamp fixture one of which parts is adapted to be secured to the standard of a portable and the other part can be so displaced or modified that another form of lamp shade or lamp globe can be accommodated.

Another object is to properly insulate the customary electric lamp socket.

To this end a two piece lamp fixture composed of wood is provided, one of which pieces is adapted to be secured to the lamp standard and the other of which pieces is adapted to be secured to said first piece and to support a lamp globe or shade.

These and other features, capabilities and advantages of the invention will appear from the subjoined detailed description of several specific embodiments thereof illustrated in the accompanying drawings, in which—

Figure 1 is an elevation illustrating a lamp having a reversible transparent or translucent globe positioned for directing the larger portion of the light-rays emanating from the lamp upwardly, which globe and lamp are supported by means constructed according to the present invention.

Fig. 2 is an elevation illustrating a lamp differing from that shown in Fig. 1 only in having a reversible globe positioned for directing the larger portion of such rays downwardly.

Fig. 2^a is a fragmental view partially in section showing means for securing the globe to the globe-supporting bracket.

Fig. 3 is a top plan view partly broken away of one of the reversible globes.

Fig. 4 is a fragmental view in elevation

and partly in section of another modified form of supporting means.

Fig. 5 is a fragmental elevation partly in section illustrating a shade having a globe supporting bracket supported by means constructed according to the present invention. 60

Fig. 6 is a fragmental view in elevation and partly in section illustrating a globe of a different form from that shown in the foregoing figures, connected at the top portion with its supporting means. 65

Fig. 7 is a detached elevational view of the main parts of the present invention separated from one another.

The lower socket receiving member 10 and the upper supporting member 11 illustrated in Figs. 4 and 7 constitute the main parts of the present invention. The lower socket receiving member 10 comprises essentially a diminished dowel pin 12 and an enlarged body portion 13. The upper portion of the body portion 13 is chamfered out to form the recess or chamber 14 and the lower portion of the body portion 13 and the dowel pin 12 are provided with a continuous bore 8 15 in communication with the recess or chamber 14. 70

The upper end of the body portion 13 is provided with an annular flange 16 adjacent to a bead 17 formed below the same 85 and set back from said bead 17 to form an annular shoulder 18 to receive the lower end of the supporting member 11, the lower end of the supporting member around its outer periphery being provided with the bead 19 90 which is disposed adjacent to the bead 17 when the members 10 and 11 are connected to one another. The flange 16 is provided with a recess 20 which registers with the recess 21 in the lower end of the supporting member 11 extending through the bead 19 and co-operates with said recess 21 to form an opening for the lamp controlling means hereinafter to be described. 95

The supporting member 11 as shown in Fig. 4 has an annular wall member through which extends a lamp when the member 11 is in position for use. The lower inner periphery of the member 11 is preferably recessed to receive the flange 16. 100

The upper end of the supporting member is curved to form the globe supporting seat 22 and along the upper end of its outer periphery there is preferably formed a bead 23. 105

When the members 10 and 11 as aforesaid are in place for use, the dowel pin 12 will be secured in the upper end of the hollow standard 24 which is similar to the standard 24' illustrated in Fig. 1, through the bore 25 of which standard 24 extend the electric cords 26, such cords 26 extending up through the bore 15 of the member 10 and being connected to the lower end of the lamp-socket 27 which is disposed in the recess or chamber 14 of the member 10. The lamp-socket 27 is provided with the usual chain guide 28 which extends through the opening formed by the registering recesses 20 and 21 to permit a chain 29 of the socket 27 to extend down the outside of the members 10 and 11. As illustrated in Fig. 4, the lamp-socket 27 extends up into the member 11 and terminates below the upper edge thereof, the lamp bulb 30 extending upward therefrom and into the globe 31, the lower edge of which rests in the seat 22 of the member 11. The members 10 and 11 are composed of an insulating material preferably wood 25 as illustrated. In view thereof it will be seen that the lamp-socket 27 will be entirely insulated and inclosed by such members 10 and 11.

In the embodiment illustrated in Fig. 4, 30 a duplex globe is illustrated having a light reflecting portion 33 and a light diffusing portion 34, the globe being positioned with its light reflecting portion adjacent to the member 11 to produce the inverted lighting effect. When the direct lighting effect is to be produced, the globe is inverted, as illustrated in Fig. 2, and if the supporting portion of the light diffusing portion 34 is of greater dimension than the supporting portion of the light reflecting portion, as appears in the present illustration, a different supporting member will be provided, such as the supporting member 11' of Fig. 2, having an annular seat portion 22' of greater diameter than the upper portion of the member 11, illustrated in Fig. 4.

If desired, instead of the member 11, a member 11^a, such as illustrated in Fig. 1, may be provided for supporting a separate globe supporting member 35 which may be composed of metal and provided with suitable vents 36, the globe 31 being secured to the supporting member 35 in any suitable manner.

If desired, instead of the member 11^a, a short member 11^b, such as illustrated in Fig. 5, may be provided for supporting the separate globe supporting member 35', whereby the globe 31 will be supported in the usual way.

If desired, on the other hand, instead of the member 11, the member 11^c, such as illustrated in Fig. 6, may be provided, the upper end of which below the bead 23' is reduced so 60 as to form a convenient seat for a clip 37 by

means of which a lamp shade 38 may be supported in the usual manner.

In the embodiment shown in Fig. 2^a, there is provided the globe supporting member 11^a, having an upwardly projecting flange 40 provided with upper recesses 41 to coöperate with the lower recesses 42 of an annular member 43, which recesses 41 and 42 of the flange 40 and annular member 43 coöperates with one another to form pockets for the springs 44, which are strained against the head 45 of the snap buttons 46 connected to said heads 45 by the stem 47, the buttons 46 being disposed on the outer peripheries of the flange 40 and annular member 43, while the heads 45 are disposed in the pockets formed by the recesses 41 and 42. The annular member 43 is secured to the flange 40 in any suitable manner. When in clamping position, the buttons 47 are strained against the lower end of the inclined surface 48 of the globes 49.

It is obvious that various changes and modifications may be made to the details of construction without departing from the general spirit of the invention.

I claim:—

1. An electric lamp fixture comprising a lamp socket receiving member and a globe supporting member both composed of an insulating material, the globe supporting member coöperating with the socket receiving member to form a complete closure for a metallic electric lamp socket, a flange at the upper end of said socket receiving member, there being an annular recess adjacent thereto to form a seat for the lower end of the globe supporting member, the flange extending into such globe supporting member.

2. In combination with a hollow lamp standard, an electric lamp socket of an electric lamp fixture comprising a lamp socket receiving member and a globe supporting member, a dowel pin on said socket receiving member extending into the upper end of the hollow lamp support, an enlarged body portion on said socket receiving member above said dowel pin having a socket for receiving said lamp socket the remaining portion of said body portion and the dowel pin being provided with a continuous bore for the passage of electric cords.

3. In combination with a hollow lamp standard, an electric lamp socket and electric cords connected to said socket, of an electric lamp fixture comprising a lamp socket receiving member and a supporting member, a dowel pin on said socket receiving member extending into the end of the hollow lamp standard, the lamp socket being supported by said lamp socket receiving member, there being a passage through said socket receiving member coöperating with the hollow standard to accommodate said electric cords.

4. In combination with a hollow lamp standard, an electric lamp socket and electric cords connected to said socket, of an electric lamp fixture comprising a lamp socket receiving member and a supporting member, a dowel pin on said socket receiving member extending into the end of the hollow lamp standard, the lamp socket being supported by said socket receiving member, there being a passage through said socket receiving member coöperating with the hollow standard to accommodate said electric cords, and a seat formed at the upper end of said supporting member for the reception of a suitable globe.
5. In combination with a hollow lamp standard, an electric lamp socket and electric cords connected to said socket, of an electric lamp fixture comprising a lamp socket receiving member and a supporting member, a dowel pin on said socket receiving member extending into the end of the hollow lamp standard, the lamp socket being supported by said socket receiving member, there being a passage through said socket receiving member coöperating with the hollow standard to accommodate said electric cords, the socket receiving member and supporting member being composed of wood and completely inclosing the lamp socket to properly insulate the same.
6. In combination with a hollow lamp standard, an electric lamp socket and electric cords connected to said socket, of an electric lamp fixture comprising a lamp socket receiving member and a supporting member, a dowel pin on said socket receiving member extending into the end of the hollow lamp standard, the lamp socket being supported by said socket receiving member, there being a passage through said socket receiving member coöperating with the hollow standard to accommodate said electric cords, the socket receiving member and supporting member being composed of wood and completely inclosing the lamp
- socket to properly insulate the same, a chain guide on said lamp socket, there being recesses in said socket receiving member and supporting member in alinement with one another to form an opening through which said chain guide may extend.
7. In combination with a lamp standard, an electric lamp socket and electric cords connected to said socket, and a lamp socket receiving member composed of wood having a dowel pin extending into the upper end of said standard, the lamp socket being supported by said socket receiving member, there being a passage through said socket receiving member coöperating with the hollow standard to accommodate said electric cords, and a seat formed at the upper end of said socket receiving member to accommodate a supporting member for any desired globe or the like.
8. An electric lamp fixture comprising a lamp socket receiving member and a globe supporting member both composed of an insulating material, the globe supporting member coöperating with the socket receiving member to form a complete closure for a metallic electric lamp socket, a flange at the upper end of said socket receiving member, there being an annular recess adjacent thereto to form a seat for the lower end of the globe supporting member, the flange extending into such globe supporting member, the globe supporting member having a flange extending upwardly therefrom, an annular member disposed on said flange, there being recesses in said upwardly extending flange and annular member to form pockets, snap buttons secured in said pockets, and springs disposed in said pockets and resiliently straining said buttons outwardly for anchoring a globe to said globe supporting member.
